UNITED STATES PATENT OFFICE.

ALONZO A. MOORE, OF WINTHROP, MASSACHUSETTS.

SWIMMING-MACHINE.

Specification of Letters Patent.

Patented Apr. 1, 1919.

1,299,000.

Application filed July 11, 1918. Serial No. 244,409.

To all whom it may concern:

Be it known that I, ALONZO A. MOORE, a subject of the King of England, residing at Winthrop, in the county of Suffolk and State of Massachusetts, have invented certain new and useful Improvements in Swimming-Machines; and I do declare the following to be a full, clear, and exact description of the invention, such as will enable others skilled in the art to which it appertains to make and use the same.

This invention relates to swimming machines, and it relates particularly to an improved foldable and adjustable machine which is propelled by foot power.

One of the objects of this invention is to properly support the body of a person in position to operate pedals to drive the device.

Another object is to provide a swimming machine which is adjustable to suit persons of different sizes and proportions;

Another object is to secure the operator against dislodgment by the action of the waves;

Another object is to provide a swimming machine which is foldable so as to be easily transportable, and which may, when folded, be placed in a suitable case for preventing identification of its character;

Another object is to provide a swimming machine which is almost entirely submerged when in use, so as to avoid detection by the enemy when the device is used as an implement of war; and

Another object is to obtain the greatest efficiency, durability, safety and usefulness, consistent with its production at a comparatively low cost.

Other objects and advantages may become apparent to persons who read the following details of description in connection with the accompanying drawings in which:

Figure 1 is a side elevation view of my improved swimming machine, the operator being indicated in broken lines, to render the operation of the device apparent to those who are familiar with the art;

Fig. 2 is a top plan view of the device illustrated in Fig. 1;

Fig. 3 is a longitudinal vertical sectional view;

Fig. 4 is a top plan view in which the flexible securing devices are in their open or inoperative position, a portion of the machine being broken out so as to disclose the transmission gearing;

Fig. 5 is a view somewhat similar to Fig. 1, but disclosing a swimming machine in a different operative position;

Fig. 6 is a transverse vertical sectional view along the line 6—6 of Fig. 1; and

Fig. 7 is a transverse vertical sectional view along the line 7—7 of Fig. 1.

Referring to these drawings in detail, in which similar reference characters correspond with similar parts throughout the several views, the machine comprises broadly a front or prow section 10, a rear or stern section 11, an adjustable connection 12 and a steering mechanism 13.

The section 10 comprises a buoyant prow member 14, flexible securing members 15, auxiliary buoys or floats 16 and wing-floats 17, the latter being pivoted or hinged at 18 to the buoyant member 14. The member 14 is preferably hollow so as to obtain the greatest buoyancy, and its top portion is concaved in one direction while being convexed in a direction at right angles to the first said direction, as clearly illustrated in Figs. 3 and 6. This construction provides a support or couch on which the body of the operator rests while he operates the machine.

In order that the operator may be securely held upon the member 14, against any tendency of the waves to dislodge him the securing members 15 are formed of canvas or other flexible material, and are each provided with a strap 19, and these straps extend across the back and shoulders of the operator and are suitably secured by buttons or other fastening device 20. In thus crossing the back of the operator the straps 19 cross each other, and the shape and relation of these securing devices are such that the arms of the operator have free play for manipulation of the steering device or for attaching any offensive device to a submarine or other craft of the enemy. The securing members 15 are also provided with connecting straps or strings 21 which may be tied or otherwise secured over the back of the operator. These securing devices are preferably connected to the body 14 by means of a rod 22 which extends through the hem of the canvas securing means 15 and through apertured lugs 23 which extend out from the body 14.

In order that the front and rear sections 10 and 11 may be moved toward or from one another, the member 14 is provided with a chamber or bore 24, and an element 25 of the

connection 12 is movable longitudinally in the bore 24. A spring 26 may be provided in the bore 24 and constitute means for moving the rod 25 outward when it is desired to 5 lengthen the machine or adjust the distance between the member 14 and the section 11. In order to secure the rod 25 against accidental movement, a set-screw 27 may be provided to engage this rod.

10 In order that sections 10 and 11 may be folded with relation to one another, I provide a pivotal joint 28 in the connection 12. It will be seen, therefore, that the section 11 may be folded upon the section 10, and the securing members 15 may then be connected together by the elements 21 so as to secure the sections of the machine in this folded condition. The connection 12 extends rearward into a hollow and buoyant stern member 29 which constitutes the body member of the rear or stern section 11. Any suitable support, such as illustrated at 30 for instance, may connect to the inner end of the connection 12 so as to secure this end of the connection in immovable relation with the body 29. A propeller 31 is carried by a propeller shaft 32 which extends through the rear end of the stern member 29, and carries a pinion 33. This pinion meshes with a gear wheel 34 which is secured on a shaft 35 so as to rotate with the latter. The shaft 35 is rotated by means of the crank levers 36 and pedals 37. Each of the pedals 37 is provided with a paddle 38 which coöperates with the propeller 31 during operation of the machine.

30 The steering device 13 consists of a rudder 34^a which is pivotally supported on arms 35^a which extend rearwardly from the member 29; a lever 36^a which is secured to the pivot 40 of the rudder 34^a; a spring 37^a which has one end secured to one end of the lever 36^a, the other end of the spring being secured to the body 29 at 30^a; a wire or cable 39 which has one end secured to the lever 36^a at 40, this 45 wire extending through suitable guides 41 and terminating adjacent to the front end of the machine; and a hand lever 42 which is pivoted at 43 to the buoyant member 14. By swinging the hand lever 42 on its pivot, 50 the rudder 34 will be moved in one direction

through the medium of the elements 36 and 39; but, on swinging the lever 42 in the opposite direction, the spring 37 is allowed to shift the rudder 34 in the opposite direction, as would appear to be obvious from an 55 observation of Figs. 1 and 2 of the drawings. A mariner's compass 44 may be provided for the convenience and safety of the operator.

From the foregoing disclosures, it will be seen that a swimming machine of this character is susceptible of many valuable uses, such as the saving of lives at bathing resorts and in case of wrecks and other disasters at sea; also, offensive and defensive operations in naval warfare, as well as for purposes of 65 pleasure and exercise.

Although I have described this embodiment of my invention very specifically, it is not intended to limit this invention to these exact details of construction and arrangement of parts, but I may make minor and necessary changes within the scope of the inventive idea disclosed in the foregoing description and following claims.

What I claim as my invention is:

1. A swimming device comprising a prow member, a propelling mechanism connected to said prow member, auxiliary floats, and flexible members secured to opposite sides of said prow member and carrying said auxiliary floats and operable to secure the body of a person on the prow member. 75

2. A foldable swimming device comprising a buoyant prow member, a propelling mechanism pivotally connected to and foldable upon said prow member, auxiliary floats, and flexible members secured to opposite sides of said prow member and carrying said auxiliary floats and operable to secure the body of a person on the prow member, 80 said flexible members also being operable to secure said propelling mechanism in folded relation to said prow member. 85

In testimony whereof I have hereunto set my hand in the presence of two subscribing 95 witnesses.

ALONZO A. MOORE.
